UNITED STATES PATENT OFFICE.

CHARLES H. SUMNER, OF TERRE HAUTE, INDIANA.

TRUSS.

Application filed March 30, 1922. Serial No. 548,089.

To all whom it may concern:

Be it known that I, CHARLES H. SUMNER, a citizen of the United States, residing at Terre Haute, in the county of Vigo and State 5 of Indiana, have invented certain new and useful Improvements in a Truss; and I do declare the following to be a full, clear, and exact description of the invention, such as will enable others skilled in the art to 10 which it appertains to make and use the same.

This invention relates broadly to an improved truss, but it has more particular reference to an improved plate for use in connection with such a device.

The principal object of the invention is to generally improve upon trusses by providing one of extreme simplicity and durability which is such in construction that it will 20 insure comfort to the wearer and will continuously exert the desired pressure against the hernia at all time regardless of the position of the body, when the truss is in use.

Another and a very important object of the invention is to provide a truss embodying a novel plate to which the pad is pivotally connected, this plate having means for connecting the ends of the body encircling 30 straps to it and being provided at its upper end with means for bearing continually against the abdomen so that when the wearer stoops, coughs, or bends his body in any manner to protrude the abdomen, the plate 35 will fulcrum on the straps and cause the pad to move inwardly and exert a greater pressure against the hernia.

A still further object of the invention is to provide a truss which is such in construction as to eliminate slipping and creeping, one which relieves the patient of pain and torture and which does not contact the body throughout its entire area, thus preventing 40 chafing and providing space for air circulation.

Other objects and advantages of the invention will be apparent during the course of the following description.

In the accompanying drawings forming a 50 part of this specification and in which like numerals are employed to designate like parts throughout the same:

Figure 1 is an elevational view, looking at the inside of the truss, with portions of 55 the straps being removed.

Figure 2 is a central vertical sectional view.

Figure 3 is a detail perspective view of the improved plate.

In the drawings, the pad 1, which may be 60 designed in any suitable way and constructed of any suitable material, is pivotally connected with a metal plate 2 preferably formed of some material which will not corrode from perspiration when contacting with the body. To provide this connection, the pad is simply formed on its inner face with spaced projections 3 against which a small plate 4 rests, this plate being bolted or otherwise connected with the projections and carrying a bolt 5 which extends through the opening 6 in the aforesaid plate 2. A nut 7 is threaded on the outer end of the bolt 5 to hold the plate 2 and pad connected together, but to permit free relative 70 movement of these parts. On its outer face at a point below the horizontal center, the plate is formed with spaced loops 8 to which the inner ends of straps 9 are connected. The straps, as is obvious, are designed to 80 surround the body above the hips and they are provided on their free ends with suitable means for connecting these ends together to permit quick detachment and adjustment. The straps will of course, be composed of elastic material. It has been before intimated that the novelty of the invention resides in the employment of the specially designed plate and it consists more especially in the formation of means at the 85 upper end of the plate for spacing the same away from the body and for affording an inward pressure on the pad. Although this result could be accomplished otherwise by especially equipping the plate with suitable 90 means, the plate is simply bent upon itself and has its end directed inwardly toward the body portion of the plate and terminating adjacent of same to form what may be conveniently termed a roll 10. This roll 100 will vary in size according to the build of the person on whom the truss is to be placed.

In applying the truss, the straps are 105 pressed around the body above the hips in the usual way and the buckle or fastening means on the ends is connected together to exert pressure against the pad 1 so as to hold it against the hernia. In practice, the shape of the pad, as before set forth, will vary to accommodate the different kinds of 110

ailments. It is obvious that when the body encircling member is drawn tight about the body, the roll 10 of the aforesaid plate 2 will be brought into contact with the abdomen and will be constantly bearing against the same. In the event that the wearer should cough or stoop, or otherwise move the body to protrude the abdomen, it is obvious that the pressure exerted against the roll 10 will tilt the lower edge of plate 2 inwardly and will likewise move the pad in the same direction to cause it to exert a greater pressure against the hernia. Hence, the pain and torture to which the patient usually is subjected at this time will be eliminated to a certain extent.

Experience has taught that a truss constructed in accordance with the invention, when applied with a properly shaped pad, will doubtless relieve the patient of much pain and torture which is experienced with the present types of patented and marketed trusses now used. The improved truss is decidedly simple in construction, light in weight, easy to place in position, and involves a new principle, in that it exerts the desired additional pressure on the hernia at the time when such pressure is required and needed. With the type of plate employed, it becomes unnecessary to provide means for escape of perspiration to prevent chafing. This is true because a very little portion of the plate contacts the body and the greater portion thereof is spaced from the same to permit free air circulation. It is to be noted the improved truss includes no springs, which are inconvenient, straps to pass under the legs, or other uncomfortable details. A truss constructed in accordance with the invention has been actually tested and has proven to give effective results beyond expectations. Free pivotal connection of the pad and plate is insured due to the novel manner of connecting the straps with the plate. These and other advantages and

features of the improved truss have been doubtless made apparent by the foregoing description. It is also thought that persons familiar with inventions of this class will doubtless be able to obtain a clear understanding of the foregoing description when considering its connection with the drawing. It therefore seems unnecessary to enter a more lengthy description.

Since probably the best results may be obtained with the construction and arrangement herein shown and described, this is taken as the preferred embodiment of the invention. However, I wish it to be understood that minor changes coming within the scope of the invention as claimed may be resorted to if desired.

I claim:

1. A truss including a flat rigid plate having its upper end bent upon itself and directed toward the wearer's body with the extremity terminating in close spaced relation to the body portion of the plate to provide a roll to bear against the abdomen, said plate being designed to be connected with the body encircling straps in a manner to permit it to fulcrum thereon, and the pad being intended to be pivotally connected to the inner face of said plate to bear against the hernia.

2. A truss comprising a pad intended to bear against the hernia, a plate pivotally connected adjacent its lower end to the intermediate portion of the pad, said plate extending above said pad and having its upper end directed first laterally and then bent to form a roll to bear against the abdomen, loops secured to the outer face of said plate, and body encircling straps connected at their inner ends to said loops, the opposite ends of the straps being adapted for connection to one another.

In testimony whereof I have hereunto set my hand.

CHARLES H. SUMNER.
